UNITED STATES PATENT OFFICE

TILLMAN CAHN, OF ELKINS PARK, PENNSYLVANIA, ASSIGNOR TO PIONEER SUSPENDER COMPANY, A CORPORATION OF PENNSYLVANIA

ADJUSTMENT SLIDE

Application filed July 30, 1930. Serial No. 471,660.

This invention relates to improvements in adjustment slides especially adapted for the adjustment of the leg bands of garters and the shoulder straps for suspenders. In order to understand the significance of this invention it should be noted that in accordance with the universal practice for many years, the adjustment slide has been a substantially flat metal member having two parallel slots. Through these slots is threaded the end of the band, which is usually an elastic webbing provided with a metal clip at the end to prevent raveling. This end with its clip is passed through one slot, then over the middle bar and back through the other slot; a considerable length of band is drawn through the two slots and then the operation repeated, that is the end is again passed through the two slots beneath the portion of the band first passed through the slots. This double threading is difficult and requires considerable time of a skilled operator, and this only after the tip has been applied to the end of the web.

The purpose of this invention is to do away with the separate end tip and double threading, thus providing a simpler and less expensive construction and also one which is more easily operated.

Referring to the drawings which illustrate merely by way of example a suitable embodiment of the invention;

Fig. 1 is a front elevation.

Fig. 2 is a fragmentary plan view.

Fig. 3 is a plan view of the adjustment slide in open position, before assembling.

Fig. 4 is a fragmentary section on line 4-4, of Fig. 1 on an enlarged scale.

Fig. 5 is a fragmentary detail in perspective also on an enlarged scale.

Fig. 6 is a view in perspective of one of the fingers on a still larger scale.

Similar numerals refer to similar parts throughout the several views.

In accordance with the present invention a

buckle formation is provided comprising two members in pivotal relationship; the slotted member 5 has a substantially flat face provided at one side margin with a series of fingers 6, which are adapted to be bent over to grip and secure permanently, between the said fingers and flat face, the web 7 near the raw or severed end thereof. Upon the opposite side margins is provided the pivot bar 8 for securing the other member 9 of the buckle. The other member 9 is provided, upon one side of the pivot axis, with an operating part or projection 10, while on the opposite side of the pivot axis is the serrated margin 11 for adjustably clamping the web 60 which is passed through the slot of member 5 after the end has been secured or gripped as above described. In locking the parts in desired position of adjustment, the web is clamped between the serrated margin 11 of member 9, and the web adjacent the margin of member 5, but upon the side opposite to that upon which the end of the web has been secured or gripped by the fingers 6.

It will also be noted that the fingers 6 are 70 slightly curved inwardly and sharpened at their outer edges as at 12 giving the same a claw shape which serves to give a more effective bite into the webbing.

The formation of the gripping fingers as 75 described secures an effective engagement with the web or band between the finger ends and the flat face of member 5.

It will thus be seen that an extremely simple and efficient adjustment slide is provided 80 which is readily associated or assembled with the band, and which is also readily manipulated to change the adjustment.

What I claim is:—
An adjustable slide for a garment supporting band, comprising sheet metal members in pivotal relationship, one member operating disengageably to clamp the web in position of adjustment, the other member comprising a flat plate having one straight mar- 85 90

gin and provided along the opposite margin thereof with a plurality of fingers adapted to be bent over the said plate but extending short of said straight margin, said fingers formed at their outer ends with straight sharpened marginal edges extending beyond the plane of their inner sides and adapted permanently to clamp the band near its end to the flat surface of said plate, the part of the band adjacent said end being bent over said fingers and extending in direction opposite the finger extension, while the portion of the band engaged by the pivotal clamp is separated from said end portion by said plate.
